UNITED STATES PATENT OFFICE

172,632

WRENCH

Frederic J. Morris, Santa Cruz, Calif.

Application April 1, 1953, Serial No. 24,302

Term of patent 3½ years

(Cl. D54—16)

To all whom it may concern:

Be it known that I, Frederic J. Morris, a citizen of the United States and a resident of Santa Cruz, California, have invented a new, original, and ornamental Design for a Wrench, of which the following is a specification, reference being had to the accompanying drawing, forming a part hereof.

Fig. 1 is a top plan view of a wrench showing my new design.

Fig. 2 is a side elevational view thereof.

Fig. 3 is an elevational view looking at the left end of the head in Fig. 2.

Fig. 4 is an elevational view looking at the right end of the head in Fig. 2, and

Fig. 5 is a fragmentary side elevational view of the left end of the wrench head partly broken away and in section.

I claim:

The ornamental design for a wrench, as shown.
